UNITED STATES PATENT OFFICE

103,140

DESIGN FOR A COMBINED WEEDING AND FERTILIZING GUN

Godfrey B. Wettstein, Portland, Oreg.

Application November 18, 1936, Serial No. 65,990

Term of patent 14 years

To all whom it may concern:

Be it known that I, Godfrey B. Wettstein, a citizen of the Republic of Switzerland, residing at Portland, in the county of Multnomah and State of Oregon, have invented a new, original, and ornamental Design for a Combined Weeding and Fertilizing Gun, of which the following is a specification, reference being had to the accompanying drawing, forming a part thereof.

Fig. 1 is a side elevation of the combined weeding and fertilizing gun, showing my new design; and

Fig. 2 is a front elevation thereof.

I claim:—

The ornamental design for a combined weeding and fertilizing gun, substantially as shown.

GODFREY B. WETTSTEIN.
